UNITED STATES PATENT OFFICE.

JOSEPH H. MORIN, OF MILLBURY, MASSACHUSETTS.

LOOM-SHUTTLE.

No. 911,068.

Specification of Letters Patent.

Patented Feb. 2, 1909.

Application filed June 15, 1908. Serial No. 438,455.

To all whom it may concern:

Be it known that I, JOSEPH H. MORIN, a citizen of the United States, residing at Millbury, in the county of Worcester and State of Massachusetts, have invented certain new and useful Improvements in Loom-Shuttles, of which the following is a specification.

My invention relates to loom shuttles, and particularly to a loom shuttle of the class shown and described in U. S. Letters Patent, No. 302,922, in which there is a spring actuated pin connected with the catch or locking device for the bobbin on the spindle, the head of which pin, on the raising of the spindle, engages with the body of the shuttle and is forced outwardly, against the action of the spring, to release the locking device.

The object of my invention is to improve upon the construction of loom shuttles of the class referred to.

In my improvements I provide a metal device, preferably of "staple" shape, with an offset head, which device is entirely independent of the spindle, and is combined with the body of the shuttle by inserting the legs or extensions of the device into holes extending in the shuttle body, one on each side of the spindle head, and directly in front of the pivot pin of the spindle, so that the offset head of the device will extend in the path of and form an abutment or engaging surface for the head of the spring actuated pin of the bobbin catch, when the spindle is raised, and the two legs or extensions on the device will extend in front of the pivot pin for the spindle head in the shuttle, will, in the constant use of the shuttle, by reason of its engagement with the picker on the opposite end of the loom from the head of the shuttle, 40 practice, that the transverse pivot pin for the spindle head in the shuttle, will, in the constant use of the shuttle, by reason of its engagement with the picker on the opposite end of the loom from the head of the shuttle, 45 wear the transverse opening through the shuttle body, and cause the pin to work loose. In my improved abutment device for the head of the spring actuated pin of the bobbin catch, by having one or both of the 50 legs or extensions on the device, located directly in front of and in the path of the pivot pin of the spindle, I provide a bearing or abutment surface for said pin, in case in the 55 constant use of the shuttle, said pin has enlarged the transverse opening, and prevent any further enlargement of said opening for

the pin, all as will be hereinafter fully described.

My invention consists in certain novel features of construction of my improvements as will be hereinafter fully described.

Referring to the drawing:—Figure 1 is a top or plan view of one end of a shuttle embodying my improvements. Fig. 2 is a side view of the end of the shuttle shown in Fig. 1, looking in the direction of arrow *a*, same figure, with a portion of the body of the shuttle broken away. Fig. 3 is a central longitudinal section, on line 3, 3, Fig. 1, looking in the direction of arrow *a*, same figure, and showing the spindle in its raised position. Fig. 4 is a side perspective view of my abutment device, detached.

In the accompanying drawing, 1 is a portion of the body of a loom shuttle, which is recessed through its central portion in the usual way, to receive the spindle 2. The spindle 2 has a head 2', with a transverse opening therethrough for the pivot pin 3, which extends transversely through the body 80 of the shuttle, in the usual way. The head 2' of the spindle 2, has a pin 4 extending through an opening therein, with a lock or catch 5 for the bobbin, attached thereto. A helically coiled expansion spring 6 extends within an opening in the head 2' of the spindle 2, and engages with one end the head 4' of the pin 4, and with its other end the lower end of the opening 2" in the head 2' of the spindle 2, see Fig. 3.

Within an opening 1' in the body of the shuttle 1, is located a pin or stud 7, having a helically coiled expansion spring 8 encircling the same. The head 7' on the pin 7 is adapted to engage the heel 2" on the spindle 2, to hold the spindle in its closed and open position.

All of the above parts may be of the usual and ordinary construction in the class of loom shuttles referred to.

I will now describe my improvements.

I provide a device 9, preferably made of wire, and preferably of the shape shown in Fig. 4, that is of "staple" or open end loop shape, having the curved top or head 9', and preferably two downwardly extending ends or legs 9". The device 9 forms the abutment or engaging surface for the head 4' of the pin 4, which is connected with the locking device 5. The abutment device 9 is combined with the body 1 of the shuttle, preferably by boring in the shuttle body

two holes 1", one on each side of the head 2' of the spindle 2, and in front of, and in the path of the pivot pin 3 for the spindle; said holes are preferably inclined toward the end 3 of the shuttle, and extend through the lower side of the shuttle, as shown in Fig. 2, and cutting away the body of the shuttle on the upper side thereof, above the pivot pin 3 of the spindle 2.

10 The abutment device 9 has its legs or ends 9" inserted into the holes 1" in the shuttle body 1, and said device is forced or driven down until the curved shaped top 9' of the device 9 extends within the upper surface 15 of the shuttle body 1, and in the path of the head 4' of the pin 4, when the spindle 1 is raised, as shown in Fig. 3. The two extended ends or legs 9" will extend directly in front of, and in the path of the pivot pin 20 3, see Fig. 2.

The advantages of my improvements will be readily appreciated by those skilled in the art.

The abutment device 9 is entirely independent of the head of the spindle, and of the pivot pin 3 therefor, and disconnected therefrom, and by its location in the shuttle body, with one of its downwardly extending ends 9" on each side of the spindle head 2', it acts 30 to bind together the sides of the shuttle body, and hold them in position at the spindle head. The downwardly extending ends 9" of the device 9, extending in front of the pivot pin 3 of the spindle, act to form a 35 bearing surface for the pivot pin 3 to strike against, in case, in the use of the shuttle, said pin wears the transverse hole in the shuttle body, as is ordinarily the case.

It will be understood that the details of 40 construction of my improvements in an abutment device for the spring actuated pin of the bobbin catch or lock mechanism may be varied if desired, and it is adapted to be combined with shuttles of any usual and 45 well known construction.

I prefer to have the extended ends or legs 9" on the spindle 9 of uniform length, but this is not essential, and one leg may be shorter than the other, and only one of the 50 legs may extend below the pivot pin 3, though I prefer to have both legs extend below the pivot pin.

Having thus described my invention, what I claim as new and desire to secure by Letters Patent is:

1. In a loom shuttle of the class described, the combination with the body of the shuttle at the spindle head end, of a metal device or staple, having an offset head extending in the path of and adapted to form an abutment for the spring actuated pin of the bobbin catch or lock, when the spindle is raised, and having its two ends extend in holes in the shuttle body on each side of the spindle head, and disconnected therefrom, and in 60 front of and in the path of the pivot pin of the spindle, to form a bearing surface for said pin to engage, in case said pin wears the transverse hole in the shuttle body.

2. In a loom shuttle of the class described, 70 the combination with the body of the shuttle at the spindle head end, of a metal device or staple having an offset head extending in the path of and adapted to form an abutment for the spring actuated pin of the bobbin catch 75 or lock, when the spindle is raised, and having one or both ends extend in holes in the shuttle body on each side of the spindle head and disconnected therefrom, and in front of and in the path of the pivot pin of the spindle, to 80 form a bearing surface for said pin to engage, in case said pin wears the transverse hole in the shuttle body.

3. In a loom shuttle, the combination 85 with the spindle pivoted at one end, and a spring actuated pin in the spindle head having the bobbin catch or lock attached thereto, of a metal abutment device to be engaged by said spring actuated pin, when the spindle is raised, and to extend in front of and 90 in the path of the pivot pin of the spindle head, said device having an offset head forming the abutment for the spring actuated pin, and one or two ends or legs which extend in holes in the shuttle body on each 95 side of the spindle head, on the inner side of the pivot pin of the spindle, and disconnected from said pivot pin, and forming an engaging surface for said pin in case said pin wears the transverse hole in the shuttle body. 100
